CLAIM

The ornamental design for a bicycle handlebar mounting plate, as shown and described.

DESCRIPTION

FIG. 1 is a side elevation view of a bicycle handlebar mounting plate showing my new design, the opposite side being a mirror image thereof, it being understood that the broken lines are for illustrative purposes only. FIG. 2 is a top plan view thereof.

FIG. 3 is a front elevational view thereof.

FIG. 4 is a rear elevational view thereof.

FIG. 5 is a bottom plan view thereof.

The characterizing feature of my design resides in the two oblong tapered holes located in the arcuate section of the plate and tapering inwardly from the top to the bottom of the holes.
